UNITED STATES PATENT OFFICE.

HENRY J. KUHLMAN, OF COLESBURG, IOWA.

MECHANICAL MOVEMENT.

1,412,183.

Specification of Letters Patent. Patented Apr. 11, 1922.

Application filed August 9, 1920. Serial No. 402,187.

To all whom it may concern:

Be it known that I, HENRY J. KUHLMAN, a citizen of the United States of America, and a resident of Colesburg, Delaware County, Iowa, have invented certain new and useful Improvements in Mechanical Movements, of which the following is a specification.

My invention relates to improvements in mechanical movements, and the object of my improvement is to supply a power transmission device adapted to change rotary to reciprocating movement.

The device has for a particular object, the actuation of a reciprocating member to efficiently vary successive parts of the power thrust thereof in one direction, as when employed in the operation of a single-acting reciprocating pump, or other mechanism in which load is moved in the power stroke of a reciprocation.

The above object has been successfully accomplished by the means which are hereinafter described and claimed, and which are illustrated in the accompanying drawings, in which Fig. 1 is an elevation of the device looking away from the source of power, with parts removed or broken away. Fig. 2 is an elevation of the inner faces of one set of the gearings of said device and of the pitman, the dotted lines showing the positional relation of a pump-barrel and its piston-rod to said mechanism. Fig. 3 is a top plan of the bracketed frame of the device, and Fig. 4 is an enlarged elevation of the connected pinions shown on a smaller scale in Fig. 2.

Similar numerals of reference denote corresponding parts throughout the several views.

The numeral 10 denotes a supporting frame for the mechanism of my device adapted to be removably clamped upon a fixed body such as the hollow pump cylinder 18. The frame 10 is formed at its forward end with a medial reentrant angle or clamping-member having laterally extending flanges 15, a clamping-member or counterpart 16 of similar shape has like flanges, both pairs of flanges contacting and orificed to receive bolt 14 secured by nuts 17, whereby said members may be tightly secured about said cylinder. A reciprocatory piston-rod 19 extends from without into the open upper end of said cylinder for actuating a piston (not shown) therein. A cross-bar 21 is rigidly secured on the upper

end of the piston-rod 19 by means of a bolt 20.

The numeral 24 denotes a pair of like pitmen, each having at opposite upper and lower ends bearing-eyes 23 and 25 respectively to receive pivotally the outer ends of pins 22 and 26 which are fixed upon the ends of the cross-bar 21, and eccentrically and adjustably upon the two stepped gears 34, the adjustment radially upon said gears of the pins 26 being in a plurality of pin-sockets 27.

The frame 10 has spaced horizontally disposed arms 11, and has integral transverse tubular bearings 12 and 13, in which are respectively rotatably mounted to project at both ends therefrom, the rotatable shafts 8 and 9. A belt-wheel 28 is splined upon the medial part of the shaft 9 between the divided halves of the bearing-member 13, and carries a driving-belt 29, which may be driven by means of any suitable source of power.

Upon the ends of the shaft 8 are splined like but reversed gear-wheels 34. Upon the ends of the other shaft 9 are splined like but reversed sets of abutting pinions 30, 31, 32 and 33.

Each gear-wheel 34 is formed with successively offset gear-segments 1, 2, 3 and 4. The innermost gear-segment 4 is concentric with the shaft 8. The opposite or outermost gear-segment 1 is eccentric, the other gear-segments 2 and 3 being also eccentric, with all their centers located in the radius of said gear-wheel which terminates medially in the segment 1.

The several gear-segments mentioned, while stepped laterally relatively to each other in abutting segments, and having different centers, nevertheless, meet or coincide tangentially in a tooth common to both the abutting segments, that is, terminal teeth of abutting ends of segments are integrally connected and continuous across both segments as shown in Figs. 1 and 2 at 5, 6 and 7, where the segments 1 and 2 have common teeth 5; the segments 2 and 3 have common teeth 6, and the segments 3 and 4 have common teeth 7.

Referring now to Figs. 1, 2 and 4, it will be observed that the sets of pinions are each contrived to fully coact regularly at the proper intervals with the said gear-segments which are individually related thereto and positioned in the same transaxial planes. For instance, the smallest pinion

30 has half the number of teeth of and its halves mesh only with the like opposite gear-segments 2; the next larger pinion 32 has twice the number of teeth of and its halves mesh only with the like opposite gear-segments 3, while the largest pinion 33 has the same number of teeth as and meshes only with the single concentric gear-segment 4. The pinion 30 rotates twice while 10 meshing with the gear-segment 1; the pinions 31 and 32 each rotate one-half a rotation while meshing with the respective gear-segments 2 and 3, and the pinion 33 rotates once while meshing with the gear-segment 4.

It will also be noticed that the several pinions 30, 31 and 32 are similarly eccentric with respect to the shaft 9, and mesh only with said eccentric gear-segments 1, 2 and 3 respectively, while the concentric pinion 33 meshes only with the concentric gear-segment 4. The pinions rotate as one, and may be made integral, or may be detachably connected as they are more easily and cheaply 25 made in the latter way. In either case, certain teeth of the abutting pinions coincide transversely to thus, in effect, produce common teeth extending across both pinions. Thus, referring to Figs. 1 and 4, the 30 teeth 35 and 36 are common to both pinions 30 and 31; the teeth 37 and 38 are common to both pinions 31 and 32, while the teeth 39 and 40 are common to both pinions 32 and 33.

35 The lengths of the different gear-segments and number of teeth thereon are operatively related to the circumferences and the number of teeth on the co-meshing pinions, and the common teeth of the abutting pinions 40 thus mesh with the common teeth of the appropriate gear-segments during each rotation, the transition of driving engagement being smoothly and effectively made from successive pinions to successive gear-segments.

45 The correlated driving-pinions and driven gear-segments thus furnish means for varying the speed and power of the pitmen 24 on the upward or power stroke 50 thereof. This varying of the speed of reciprocation of the pitmen is due to the decreasing or acceleration of the speed of rotation of the stepped gears while their eccentric segments are driven by the eccentric pinions. This variation of the speed 55 of rotation of the gears during one part of each rotation, moves the pitmen at the maximum stress part of the power-stroke cycle of their reciprocation at lowest speed, 60 and this fits the mechanism for use with single-acting reciprocating pumps in the conversion of rotary into reciprocating movements. The concentric segments 4 of the gears 34 allow the idle return stroke 65 of the pitmen to be at greater speed, while

also affording means of transition between the eccentric segments 3 without abrupt change in the transition of the pinions from one segment to the other.

70 My improved gearing in slowing up the speed of movement of the pitman to a lowest speed at the point of greatest load stress and then accelerating the speed to the beginning of the idle stroke, permits the employment of a prime motor supplying a maximum power of about one-half of that of a motor such as is required when the ordinary circular pinion and gear are used. This is due to the said reduction of speed to the lowest when the power stroke is at its 80 maximum loading where all the power is used, instead of there otherwise being a necessity for a doubled motive power to carry the pitman at high constant speed past this point of maximum loading.

85 It is to be understood that the number and relative arrangements of the pinions and intermeshing gear-segments of my device may be varied to produce varied actions on the pitmen, without departing from the principles of the invention.

Having described my invention, what I claim as new and desire to secure by Letters Patent, is:—

1. In combination, a rotatable gear-wheel 95 composed of stepped segments in different transaxial planes, a rotatable driving-shaft, pinions fixed on said driving-shaft to intermesh with certain of said stepped segments at certain stages of the rotation of said 100 shaft, one segment of said gear-wheel being eccentric with longest radius, the smallest of said pinions being eccentric on said shaft and intermeshing with said longest radius segment, like opposite eccentric pairs 105 of said stepped segments being in the same transaxial plane, and others of said pinions of different and larger sizes than the first-mentioned pinion being eccentric on said shaft and intermeshing respectively 110 with said like pairs of eccentric gear-segments, and a pitman terminally pivotally connected to said gear-wheel at a location opposite and aligned diametrically with the medial radius of the first-mentioned gear- 115 segment.

2. In a device of the character described, a gear-wheel composed of eccentric segments stepped in different transaxial planes, a pitman pivotally connected to said gear-wheel, 120 a driving-shaft, and eccentric pinions fixed on said driving-shaft to intermesh in succession with said segments, to impart to said gear-wheel on the power-stroke imparted by it to said pitman increasing effort to the 125 place of maximum load and decreasing effort from said place of maximum load.

Signed at Waterloo, Iowa, this 23rd day of July, 1920.

HENRY J. KUHLMAN.
